FIG. 3.

FIG. 4.

FIG. 5.

UNITED STATES PATENT OFFICE

HUGH S. BRADY AND JOHN J. WILLIAMS, OF WHEELING, WEST VIRGINIA, ASSIGNEES
TO HAZEL-ATLAS GLASS CO., OF WHEELING, WEST VIRGINIA, A CORPORATION OF
WEST VIRGINIA

CLOSURE FOR CONTAINERS

Application filed December 29, 1928. Serial No. 329,159.

The cap described herein is made, as usual, of ordinary sheet tin, which is rigid and strong; is of the side-seal type; and is used upon containers either with or without a 5 finish.

One of the advantages of the cap resides in the provision of means to take care of any excess rubber of the gasket, resulting from irregularities in the container.

10 Another advantage of the cap resides in the particular arrangement by which suitable places are provided about the cap for the application of a cap removing tool.

Another advantage of the cap resides in 15 the provision, in a cap of this type, of centering and guiding tabs.

Other objects of the invention consist in providing a cap which is inexpensive in manufacture, highly efficient in operation on containers either with or without a finish, which is easily applied to a container and is not deformed, and which is easily removed and without deformation, so that it possesses a 20 reseal value.

25 Other objects and advantages of the cap will be apparent to those skilled in the art.

For a complete description of the cap, reference is to be had to the accompanying drawings; in which

30 Figure 1 is a perspective view of a container with the cap applied thereto.

Figure 2 is a side elevational view of the cap and container.

Figure 3 is a transverse vertical sectional 35 view of the cap.

Figure 4 is a fragmentary sectional view of the cap applied to a container without a finish, such as a tumbler; and

40 Figure 5 is a view similar to Figure 4, but showing the cap applied to a container having a finish of any usual form.

As stated hereinbefore, the cap is made of sheet tin which is rigid and strong; and the cap includes the usual top 1 having an 45 annular groove 2 at the periphery thereof, and a rectangular gasket 3 having its upper end seated in the groove. The structure thus far described is old and well known. But in accordance with the present invention, this 50 ordinary groove 2 is of considerably greater

width than the initial thickness of the gasket. Also, an annular flange 4 depends from the periphery of the groove 2, and this flange terminates with an inturned horizontal flange 5, from which inturned flange depends the skirt proper, as indicated by numeral 6. By reference to Fig. 3, it will be noted that this construction provides a pocket 7, which extends from the inturned flange 5 to the top of the groove 2, and which is adapted to receive, when the cap is applied to a container, any excess rubber of the gasket resulting from irregularities in the container. The provision of this pocket constitutes a distinct improvement.

The skirt 6 terminates with a downwardly and inwardly inclined flange 8, which serves to interlock the cap and gasket; and it will be understood, of course, that the pocket 7 also serves as an interlocking means to some extent, though its primary purpose is to take care of excess rubber resulting from irregularities in the container. A plurality of guide tabs 9 depend from the inclined flange 8. The number of the guide tabs employed is, of course, merely a matter of choice. These tabs have no other function than to center and guide the caps onto the containers, and therefore the tabs may be inclined outwardly, or they may be vertical as illustrated in the drawings. Inasmuch as these tabs center and guide the cap, it is desirable that the tabs should have some resiliency; we therefore preferably, though not necessarily, increase the resiliency by providing cut-out portions 10 at the ends of the tabs. By reason of these cut-out portions 10, variation is taken care of, and also the cap is more easily removed. The provision of these guide tabs on a cap 80 of this type, constitutes a distinct improvement.

Between the guide tabs, the cap terminates with the inclined flange 8 which may extend inwardly to the wall of the container, or may extend inwardly only a very slight distance, as indicated at the right hand end of Figure 3. These cut-out portions between the guide tabs constitute a material improvement, in that they provide suitable places for the application of a cap removing tool. It is well known,

of course, that considerable difficulty is usually encountered in the removal of vacuum caps, and one of the difficulties is that such caps are so constructed that a cap removing tool cannot be easily applied. In the present construction the skirt is spaced from the container by the sealing gasket, and by providing these cut-out portions a hook or other device can be engaged under the skirt and the cap can thus be pulled off easily.

From the foregoing description it will be apparent that the cap disclosed herein presents numerous advantages. The cap is easily applied; no deformation is necessary; it is easily removed; and is inexpensive in manufacture and highly efficient in operation.

It will be understood, of course, that the cap is subject to modifications in various respects, without departing from the spirit of the invention, and it is intended that all such modifications be included within the scope of the appended claims.

What we claim is:

1. A receptacle closure made of tin and including a top and a depending skirt, a gasket arranged in the skirt, a pocket extending around the top at its periphery and of substantially greater width than the thickness of the gasket, a pocket extending around the skirt at the top thereof and communicating with the first-mentioned pocket, said pockets adapted to receive any excess rubber of the gasket resulting from irregularities in the container.

2. A receptacle closure made of tin and including a top and a depending skirt, a gasket arranged in the skirt, a pocket extending around the top at its periphery and of substantially greater width than the thickness of the gasket, a pocket extending around the skirt at the top thereof and communicating with the first-mentioned pocket, said pockets adapted to receive any excess rubber of the gasket resulting from irregularities in the container, centering and guiding tabs extending downwardly from the skirt, and cut-out portions between the tabs for the application of a removing tool.

3. A receptacle closure including a top and a depending skirt, a gasket adapted to be arranged in the skirt, a pocket extending around the skirt at the top thereof and adapted to receive any excess rubber of the gasket due to irregularities in the container, centering and guiding tabs extending downwardly from the skirt, and cut-out portions between the tabs for the application of a removing tool.

4. A receptacle closure including a top and a depending skirt, a gasket adapted to be arranged in the skirt, a pocket extending around the skirt at the top thereof and adapted to receive any excess rubber of the gasket due to irregularities in the container, centering and guiding tabs depending from the

skirt, said tabs having cut-out portions to increase the resiliency thereof.

5. In combination with a receptacle, a closure including a top and a depending skirt, a gasket arranged between the skirt and the receptacle, the lower edge of the gasket being substantially flush with the lower edge of the skirt, inturned flanges as intervals about the lower edge of the skirt and projecting slightly beneath the gasket, and centering and guiding tabs also at intervals about the lower edge of the skirt and projecting downwardly therefrom.

6. In combination with a receptacle, a closure including a top and a depending skirt, a gasket arranged between the skirt and the receptacle, a pocket extending around the top at its periphery and of substantially greater width than the thickness of the gasket, a pocket extending around the skirt and at the top thereof and communicating with the first-mentioned pocket, said pockets adapted to receive any excess rubber of the gasket resulting from irregularities in the receptacle, the lower edge of the gasket being substantially flush with the lower edge of the skirt, inturned flanges at intervals about the lower edge of the skirt and projecting slightly beneath the gasket, and centering and guiding tabs also at intervals about the lower edge of the skirt and projecting downwardly therefrom.

7. A receptacle closure including a top provided with a pocket extending around its periphery, a skirt depending from said top, a gasket adapted to be arranged in the skirt with its upper edge positioned in said pocket, the lower edge of the gasket being substantially flush with the lower edge of the skirt, and centering and guiding tabs at intervals about the lower edge of the skirt and projecting downwardly therefrom.
